[57] CLAIM

The ornamental design for a wall mounted guitar bracket, as shown and described.

DESCRIPTION

FIG. 1 is a side elevational view of a wall mounted guitar bracket showing my new design, the opposite side being a mirror image;

FIG. 2 is a front elevational view thereof;

FIG. 3 is a rear elevational view thereof;

FIG. 4 is a top plan view thereof;

FIG. 5 is a bottom plan view thereof.
